US00D691255S

(12) **United States Design Patent**
Abbondanzio et al.

(10) **Patent No.:** US D691,255 S
(45) **Date of Patent:** ** Oct. 8, 2013

(54) **DISPENSER HOUSING**

(71) Applicants: **Matthew Abbondanzio**, Milwaukee, WI (US); **George Kyaw Maung Aye**, Chicago, IL (US); **Jeffrey Allan Gershune**, Chicago, IL (US); **Joseph Thomas Graceffa**, Chicago, IL (US); **Maria Dora Lalli**, Portland, OR (US); **David Brian Seal**, Chicago, IL (US)

(72) Inventors: **Matthew Abbondanzio**, Milwaukee, WI (US); **George Kyaw Maung Aye**, Chicago, IL (US); **Jeffrey Allan Gershune**, Chicago, IL (US); **Joseph Thomas Graceffa**, Chicago, IL (US); **Maria Dora Lalli**, Portland, OR (US); **David Brian Seal**, Chicago, IL (US)

(73) Assignee: **S.C. Johnson & Son, Inc.**, Racine, WI (US)

(**) Term: **14 Years**

(21) Appl. No.: **29/454,815**

(22) Filed: **May 14, 2013**

(57) **CLAIM**

The ornamental design for a dispenser housing, as shown and described.

DESCRIPTION

FIG. 1 is an isometric view of a top, front, and right side of an ornamental design for a dispenser housing;

FIG. 2 is a front elevational view of the housing of FIG. 1; FIG. 3 is a rear elevational view of the housing of FIG. 1; FIG. 4 is a right side elevational view of the housing of FIG. 1;

FIG. 5 is a left side elevational view of the housing of FIG. 1; FIG. 6 is a top plan view of the housing of FIG. 1; FIG. 7 is a bottom plan view of the housing of FIG. 1; and, FIG. 8 is an alternative embodiment of the top plan view of FIG. 6.

The broken line showing of the subject matter shown above is for the purpose of depicting environmental structure only and forms no part of the claimed design.
